UNITED STATES PATENT OFFICE.

WILLIAM ORR, OF TRENTON, NEW JERSEY, ASSIGNOR TO THE NEW JERSEY WIRE CLOTH COMPANY, OF TRENTON, NEW JERSEY, A CORPORATION OF NEW JERSEY.

FIREPROOF CONSTRUCTION.

SPECIFICATION forming part of Letters Patent No. 693,429, dated February 18, 1902.

Application filed November 6, 1900. Serial No. 35,622. (No model.)

To all whom it may concern:

Be it known that I, WILLIAM ORR, a citizen of the United States, residing at Trenton, county of Mercer, and State of New Jersey, have invented certain new and useful Improvements in Fireproof Constructions, fully described and represented in the following specification and the accompanying drawings, forming a part of the same.

10 This invention relates to an improved fireproof construction of that class employing concrete or similar plastic material in combination with reticulated metal and adapted especially for use as a floor or ceiling construction and to an improved building material for fireproof constructions. I aim particularly at the formation of a floor or similar construction in which the metal parts employed shall be of light weight, while at the same time securing the desired strength and fireproof qualities in connection with the concrete or similar plastic material and which may be built rapidly and cheaply.

As a full understanding of the invention can best be given by an illustration and a detailed description of constructions embodying the same, such a description will now be given in connection with the accompanying drawings, forming a part of this specification and 30 showing the invention as applied in constructions of the preferred forms, and the features forming the invention will then be specifically pointed out in the claims.

In the drawings, Figure 1 is a cross-section 35 of a floor construction in the process of formation with the centering in place, the concrete being removed in the left half of the figure to show the construction. Fig. 2 is a cross-section of the completed construction. Fig. 3 is a plan view of the beams with the reticulated metal in place before bending the ends of the rods about the beams. Fig. 4 is a view similar to Fig. 3, showing a modified form of reticulated metal. Fig. 5 is a partial cross-section of a completed floor, showing a modified construction. Fig. 6 is a partial section 45 of a complete floor similar to that of Fig. 2, showing a beam protection and illustrating the preferred corrugated form of the rods. Fig. 50 7 is a view similar to Fig. 5 with the beam

protection of Fig. 6. Fig. 8 is a perspective view of the beam-protection clip in position on beam-flange.

Referring now especially to Figs. 1 to 3, A designates the floor-beams, which are shown 55 as of the common I form, although the invention may be applied with beams of other form; B, the temporary centering which is used for molding and supporting the green concrete, this centering being shown as supported from the tops of the beams by hangers C, although it may be supported in any other way, and D is the concrete which is filled in on the centering B to form the floor and in which is embedded the reticulated metal 65 which forms the especial feature of the present invention, this reticulated metal in the form shown in Figs. 1 to 3 consisting of metal rods E, extending from beam to beam and hooked over the tops of the beams, and strands F, extending longitudinally of and between the beams and secured to the rods so as to form therewith a sheet of reticulated metal 70 extending longitudinally of the beams with the rods E projecting at opposite sides of the 75 sheet. As shown in Figs. 1 to 3, the longitudinal strands F of the reticulated metal run parallel with the beams and each is formed of two crossed or twisted wires with the rods E inserted between the wires of the strands, 80 and this form of construction with two or more wires either twisted or crossed together and inclosing the rods E and extending parallel with the beams is preferred; but strands of single wires may be used, and the wires 85 and rods may be otherwise arranged and secured together by welding or any other form of attachment within the invention, considered broadly, and instead of the wires running parallel with the beams netted or other 90 meshed form of wire fabric or other form of reticulated metal may be used in connection with the rods E—such, for instance, as the netting illustrated in Fig. 4. The distance between the rods E will be such as to obtain 95 the requisite tensile strength of the metal in connection with the concrete, and in such constructions as shown in Figs. 1 and 2 the transverse wires F or mesh of the woven or netted wire or other reticulated metal will be such 100

as to allow the concrete to be filled through the meshes from above upon a centering below the metal, so as to entirely embed the latter.

The method of application in the construction shown in Figs. 1 and 2 is as follows: A centering of suitable form is supported below or between the beams, as shown in Fig. 1. The reticulated metal formed of the rods E and wire strands F is then stretched in place 10 with the sheet running longitudinally of and between the beams and with one end of each rod hooked over a beam and the other ends of the rods extending straight over the top of the adjacent beam, as shown in Fig. 3. 15 These straight ends of the rods are then turned down and bent around the top flange of the beam into the position shown in Fig. 1, which bending acts to draw the reticulated metal tight between the beams, so that the 20 rods act properly as tensile members for the concrete, while at the same time serving as tie-rods for the beams. The concrete is then filled in through the metal upon the centering, as shown at the right in Fig. 1, after which 25 the centering is removed, leaving a complete floor construction, as shown in Fig. 2, which shows also the usual plaster finish G on the under side of the floor.

It will be seen that the construction above 30 described provides a very strong concrete floor or similar structure with light metal parts, the rods E forming efficient tension-rods for the concrete, and tie-rods between the beams and the longitudinal strands F, in 35 connection with rods E, securing the desired strong anchorage for the concrete to the metal.

It will be seen also that the reticulated metal is simple and cheap of manufacture, as it may be made up into long sheets or webs 40 of the proper span width with the rods E inserted at intervals and that it may be placed in position rapidly and accurately without skilled labor by simply spreading the continuous sheet of metal longitudinally between 45 and upon the beams and bending the rods E about the beams to adjust and hold the metal in place. While this reticulated metal is especially designed for use in constructions in which concrete or similar plastic material 50 is filled through the reticulated metal to form a floor or similar construction with the metal entirely embedded therein and forming tension, anchorage, and tie-rod members, as above described, in which case the meshes of 55 the metal will be of such size as to permit the concrete or similar plastic material to pass freely through them, (and the invention consists in part of such constructions and material therefor,) it will be understood that similar metal with meshes of such size as to support 60 the concrete may be used, so that the concrete may be filled in upon it without a centering to form a construction consisting of a light metal support and concrete or similar plastic material thereon. Similar metal of small mesh may be used also in forming 65 plaster ceilings and similar structures, the

web of metal then being extended between either the tops or bottoms of the beams or other supports and the rods E hooked over 70 the supports. In the case of flanged beams it is apparent that such ceilings may readily be suspended by hooking the rods of the metal web about the bottom flanges of the beams. The broader claims herein include such constructions of reticulated metal. 75

While it is preferable that the rods E should be hooked over the beams in floor constructions, so as to form tie-rods and hold the reticulated metal under tension secured by 80 bending the ends of the rods around the beams, yet in the case of short spans it is possible to use the metal to advantage without hooking the rods over the beams, but simply embedding the metal in the concrete to serve 85 as anchorage and tension members therefor. In this case I prefer to bend the ends of the rods E in such a manner that these ends will make an anchorage in the concrete in which they are embedded. Such a construction is 90 shown in Fig. 5 with the ends of the rods E bent upward at 1 to secure the desired anchorage. Otherwise the construction is substantially the same as shown in Fig. 2, except that the 95 plaster finish G is omitted. It will be understood that in making the construction shown in Fig. 5 the concrete will be partially filled in on the centering to form a bed, the reticulated metal then laid on, and the filling in completed, as common in this art. It will probably be 100 found preferable to slightly corrugate the rods E to obtain a better anchorage in the concrete, although straight rods may be used, as shown in Figs. 1 to 5. It is frequently desirable 105 also to provide a fireproof protection for the webs and bottoms of the beams by inclosing a space about them with reticulated metal and filling this space with concrete or similar plastic material, and I have devised a 110 novel form of support for securing the required offset of the reticulated metal from all points of the bottom flanges of the beams, which in itself forms a specific feature of the present invention.

In Fig. 6 I have shown a construction employing my improved reticulated metal in the same manner as shown in Fig. 2, but with the rods E slightly corrugated for anchorage of the concrete and with a beam protection consisting of the concrete D, filling the space 115 inclosed by sheets of wire lathing H, supported above by the rods E and offset from the lower flanges of the beams by my improved offsetting-clips I, which offsetting-clips are shown in detail in Fig. 8. The lathing H of the beam protection is shown as covered with the usual plaster finish G, continuing the finish on the under side of the floor structure. The space inside the lathing H or some part of it may be left empty, as an 120 air-space, if desired. These offsetting-clips I consist of a metal rod bent to form the body 125 3, extending longitudinally of the beams for the offsetting and support of the lathing, and 130

two horizontal arms 4, which have at their ends U portions 5, which tightly embrace the flange of the beam, so as to hold the clip in position, and vertical arms 6, extending downward below the flange of the beam to give the required offset of the lathing and space under the flange of the beam. These clips are arranged along the flange of the beam at suitable intervals and on opposite sides of the beam to give the desired support of the lathing. It will be seen that these offsetting clips are very convenient and cheap of manufacture and may be put in place on the beams very rapidly, and that by the length and extent of the vertical and horizontal arms formed by bending the rods just the desired offsetting of the lathing below and at opposite sides of the beam may be secured. This beam protection, with my improved clips, may obviously be used not only with the construction in which the rods E are hooked over the tops of the beams, but also with the reticulated metal embedded in the concrete without such tie-rod feature, and a construction of this form is shown in Fig. 7, which is the same as Fig. 5, with the beam protection of Fig. 6 added.

What I claim is—

1. A floor or similar construction comprising beams, sheets of reticulated metal extending longitudinally of the beams and of such width that the span between adjacent beams is covered by a single sheet and having rods extending transversely to the beams and forming a part of the sheets and projecting from the opposite edges of the sheets of reticulated metal, and a filling of concrete or similar plastic material between said beams, substantially as described.

2. A floor or similar construction comprising beams, sheets of reticulated metal extending longitudinally of the beams and of such width that the span between adjacent beams is covered by a single sheet and having rods extending transversely to the beams and forming a part of the sheets and projecting from the opposite edges of the sheets of reticulated metal, and a filling of concrete or similar plastic material between said beams and in which the reticulated metal is entirely embedded, substantially as described.

3. A floor or similar construction comprising beams, sheets of reticulated metal extending longitudinally of the beams and of such width that the span between adjacent beams is covered by a single sheet and having rods extending transversely to the beams and forming a part of the sheets and projecting from the opposite edges of the sheets of reticulated metal, said rods being hooked over the tops of the beams to form tie-rods between the beams, and a filling of concrete or similar plastic material between said beams, substantially as described.

4. The combination with beams, of sheets of reticulated metal extending longitudinally of the beams and of such width that the span

between adjacent beams is covered by a single sheet and having rods extending transversely to the beams and forming a part of the sheets and projecting from the opposite edges of the sheets of reticulated metal, said rods being hooked over the tops of the beams to form tie-rods between the beams, and a filling of concrete or similar plastic material between said beams and in which the reticulated metal is entirely embedded, substantially as described.

5. The combination with beams, of sheets of reticulated metal extending longitudinally of the beams and of such width that the span between adjacent beams is covered by a single sheet and having rods extending transversely to the beams and forming a part of the sheets and projecting from the opposite edges of the sheets of reticulated metal, said rods being hooked over the tops of the beams to form tie-rods between the beams, and a filling of concrete or similar plastic material between said beams and in which the reticulated metal is entirely embedded, substantially as described.

6. The combination with beams, of sheets of reticulated metal extending longitudinally of and between the beams and of such width that the span between adjacent beams is covered by a single sheet and consisting of strands extending longitudinally of the beams with rods forming a part of the sheets and extending transversely to the beams and secured to the longitudinal strands and hooked around the beams, substantially as described.

7. The combination with beams, of sheets of reticulated metal extending longitudinally of and between the beams and of such width that the span between adjacent beams is covered by a single sheet and consisting of strands extending longitudinally of the beams and formed of crossed or twisted wires with rods extending transversely of the beams and between the wires of the longitudinal strands and hooked around the beams, substantially as described.

8. An article of manufacture consisting of building material formed of a sheet of reticulated metal of such width as to cover the span between beams or other supports with which it is to be used and having supporting-rods woven therein or secured thereto and projecting beyond the sheet and adapted to be hooked around the supports to hold the reticulated metal in place, substantially as described.

9. An article of manufacture consisting of building material formed of a sheet of reticulated metal of such width as to cover the span between beams with which it is to be used having cross supporting-rods woven therein or secured thereto and projecting beyond the sheet and adapted to be hooked over the flanges of adjacent beams to support the retic-

ulated metal and form tie-rods between the beams, substantially as described.

10. An article of manufacture consisting of building material formed of a sheet of reticulated metal of such width as to cover the span between beams or other supports with which it is to be used having supporting-rods woven therein or secured thereto and projecting beyond the sheet for securing the latter in place, 10 said reticulated metal being of such mesh as to permit concrete or similar plastic material to be filled in from above through the meshes, substantially as described.

11. An article of manufacture consisting of 15 building material formed of longitudinal strands and cross supporting-rods secured to said strands and projecting beyond the sheet, substantially as described.

12. An article of manufacture consisting of 20 building material formed of longitudinal strands consisting of twisted or crossed wires and cross supporting-rods inserted between the wires of the strands and projecting beyond the sheet, substantially as described.

25 13. The combination with the beam A, of the offsetting-clip I consisting of a single piece of metal bent to form a body 3 extending longitudinally of the beam and arms 4 extending transversely to and below the beam 30 with U-shaped portions 5 adapted to embrace the flange of the beam and support the clip, substantially as described.

14. The combination with beam A, of the offsetting-clip I consisting of a single piece of 35 metal bent to form a body 3 extending longitudinally of the beam, arms 4 extending transversely to and below the beam with U-shaped portions 5 adapted to embrace the flange of the beam and support the clip, and 40 vertical arms 6 for offsetting the body of the clip below the beam, substantially as described.

15. The combination with beam A, of a series of clips I on opposite sides of the beam, 45 said clips consisting of a single piece of metal

bent to form a body 3 extending longitudinally of the beam, arms 4 extending transversely to and below the beam with U-shaped portions 5 adapted to embrace the flange of the beam and support the clip, vertical arms 50 6 for offsetting the body of the clip below the beam, and reticulated metal H extending below and about the beams and offset therefrom by the clips, substantially as described.

16. The combination with beams A and 55 a fireproof floor construction between the beams, of a series of clips I on opposite sides of the beams, each of said clips consisting of a single piece of metal bent to form a body 3 extending longitudinally of the beam, arms 4 60 extending transversely to and below the beam with U-shaped portions 5 adapted to embrace the flange of the beam and support the clip, vertical arms 6 for offsetting the body of the clip below the beam, reticulated metal H extending from said floor downward and about the bottoms of the beams and offset from the beams by said clips, and plastic material on 65 said metal, substantially as described.

17. Offsetting-clip I consisting of a single 70 piece of metal bent to form a body 3 and arms 4 extending transversely to the body with U-shaped portions 5 at the ends of the arms adapted to embrace the flange of a beam, substantially as described.

18. Offsetting-clip I consisting of a single 75 piece of metal bent to form a body 3 and arms 4 extending transversely to the body with U-shaped portions 5 at the ends of the arms adapted to embrace the flange of a beam, 80 and vertical arms 6 for offsetting the body of the clip below the beam, substantially as described.

In testimony whereof I have hereunto set my hand in the presence of two subscribing 85 witnesses.

WILLIAM ORR.
